CLAIM

The ornamental design for a camera, as shown and described.

DESCRIPTION

FIG. 1 is a front perspective view of a camera showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The portions illustrated in dashed broken lines and the portions illustrated within dashed broken lines depict portions of the camera in which the design is embodied that form no part of the claimed design.

The dot-dash lines denote the boundary of the claim and form no part of the claimed design.

1 Claim, 8 Drawing Sheets
